WELT BUTTING AND TACKING MACHINE

Eric A. Holmgren, Beverly, Mass., assignor to
 United Shoe Machinery Corporation, Flemington, N. J., a corporation of New Jersey

Application September 2, 1941, Serial No. 409,254

12 Claims. (Cl. 12—67)

This invention relates to welt butting and tacking machines, and particularly to improvements in machines of this kind for facilitating the welt butting and tacking operations when performed on shoes provided with so-called two-piece storm welts.

Two-piece storm welts, sometimes referred to as bi-welts, comprise a welt strip and a separate bead portion which, during the weltting operation, becomes secured to the welt strip to form a seal of caulked bead between the welt and upper in the inseam crease. To improve the appearance of the joint between the ends of the two-piece welt and the heel seat of the shoe it has been proposed to butt the welt strip only and to bend the unsecured and unsevered ends of the bead portion, which extends rearwardly beyond the butted ends of the welt strip, inwardly toward the middle of the shoe bottom where they are secured in place by tacks. The machine disclosed in United States Letters Patent No. 1,747,533, granted February 18, 1930, on an application of Fred L. MacKenzie, is provided with fixed means for deflecting the ends of the bead portion of a two-piece welt inwardly when the shoe is placed in the machine to accomplish this result.

It is an object of this invention to provide, in a welt butting and tacking machine, improved means for handling two-piece storm welt in a novel manner and so that the unsecured ends of the bead portions are not severed but are positively moved inwardly, towards the middle of the shoe bottom, during the operation of the machine and after the butting of the welt strips. To this end there are provided, as a feature of this invention, novel deflecting means, associated with the crease finders and welt butting anvils, which are arranged to engage the bead portions of the welt beneath the anvils and which are movable, during the operation of the machine and subsequently to the welt butting operation, to bend the unsevered ends of the bead portions inwardly toward the middle of the shoe bottom in position for securing to the shoe bottom by tacks during the tacking operation. More particularly, each deflecting means comprises a movable deflector, arranged between a crease finder and an anvil and having a portion extending inwardly toward the shoe and rearwardly beneath the anvil for engagement with an unsecured end of the bead portion of a two-piece welt, which is operable to bend the end of the bead portion inwardly of the shoe.

It will be understood, in handling two-piece storm welt in the above manner, that the ends

of the welt strip are supported on top of the welt butting anvils while the ends of the unsecured bead portion are placed beneath the anvils so as not to be severed in the welt butting operation. When set to receive a shoe of any particular size, the crease finder assemblies of welt butting machines are usually positioned by some form of adjusting means so as to be separated just enough for the crease finders to enter the welt crease on the opposite sides of the shoe, with the anvils of the assemblies extending inwardly beyond and beneath the welt, when the shoe is presented to the machine. Ordinarily, the shoe is introduced by inserting it rearwardly into the machine, sliding the anvils beneath the welt ends. With two-piece storm welts it is difficult to do this so that the unsecured ends of the bead portion are located beneath, and the welt strips positioned on top of, the anvils.

Accordingly, a further feature of this invention resides in the provision in a welt butting machine of means for moving the crease finder assemblies out of their adjusted positions to facilitate the introduction of shoes having two-piece welts and for thereafter returning them to their original adjusted positions. More specifically, this means comprises a toggle mechanism associated with the means for adjusting and operating the crease finder assemblies of a welt butting machine which is operable quickly to separate the crease finder assemblies, to facilitate the introduction of two-piece welt work, and which is thereafter operable to return the assemblies to their original position without disturbing the setting of the adjusting means.

These and other objects and features of the invention will become apparent from the following detailed description of the preferred embodiment of the invention, disclosed in the accompanying drawings, and will be pointed out in the claims.

In the drawings,
 Fig. 1 is a plan view of a portion of a welt butting machine embodying the features of this invention, parts of the machine being broken away, or omitted, to simplify the disclosure;

Fig. 2 is an end elevation of a portion of the mechanism shown in Fig. 1;

Figs. 3, 4 and 5 are enlarged views of the crease finder assemblies shown in Fig. 1, but showing the parts in several different positions assumed at various stages in the operation of the machine.

The illustrative embodiments of the features of this invention are herein shown applied to a welt butting and tacking machine of the type disclosed in the patents to Holmgren Nos. 2,202,005 and

2,206,897. As will be understood from the disclosures of these patents, machines of this kind are provided with means for supporting the end portions of a welt during the butting operation, which means include crease finder assemblies that are moved inwardly by power-operated means to tighten the upper on the last prior to the welt tacking operation. The crease finder assemblies include crease finders and anvils and, in accordance with the teachings of Patent No. 2,206,897, the crease finder assemblies of the herein illustrated machine also have deflectors which are movable to bend end portions of the welt inwardly of the shoe bottom. In the machines of the mentioned patents, and in the machine herein illustrated, the crease finder assemblies are mounted on swinging brackets and are connected to heads which carry the tacking and pounding instrumentalities and which are opened and closed by the power operated means during the operation of the machine. With the differences to be noted below, the mechanism for opening and closing the heads, which carry the tacking and pounding mechanism in the machine herein illustrated, is similar to that provided in the machines of these two patents, and shown in Fig. 23 of Patent No. 2,202,005, while the crease finder assemblies and their operating mechanisms are similar to those shown and described in Patent No. 2,206,897.

Referring to the drawings, the crease finder assemblies include blocks 68, 68 carried by swinging brackets 70, 70 in which are mounted deflectors 60, 60, anvils 97, 97, and crease finders 100, 100. Reference characters similar to those used in Patent No. 2,206,897 are employed to designate these corresponding parts in the several figures of the drawings, and reference may be made to pages 3 and 4 of that patent for a more detailed description of the construction and mode of operation of these elements. Portions of levers 132, 132, for retracting the anvils, and also of shafts 90, 90, for operating the deflectors 60, 60 are also shown in Fig. 1.

The herein illustrated deflectors 60, 60, however, are novel, and as will be seen from Fig. 3, comprise portions 60a, 60a, which extend inwardly beneath the anvils 97, 97. These inwardly extending portions have downwardly and outwardly beveled operating faces 60b, 60b which converge slightly in an inward direction, as shown. The deflectors are also provided with concave surfaces 60c, 60c, the purpose of which will presently appear.

The operation of the improved deflectors for bending in the unsecured ends of the bead portion of a two-piece storm welt is as follows:

Fig. 1 shows a shoe provided with two-piece storm welt in position in the machine prior to the welt butting and tacking operation. Each end of the welt W is over an anvil 97 and the crease finders 100, 100 are in the welt creases on opposite sides of the shoe. The unsecured ends of the bead portion b, b of the two-piece welt are, however, positioned beneath the anvils and, as shown, are deflected inwardly a slight amount by the operating faces 60b, 60b of the deflectors. In order to facilitate introduction of bi-welt work into the machine the crease finder assemblies are separated from their usual adjusted position, by mechanism which constitutes another feature of this invention, to the open position shown in Fig. 3 where the anvil on one side is inserted between the welt W and its bead portion b. Now,

as the crease finders are returned to the adjusted position of Fig. 1, the anvil on the other side is likewise inserted between the welt W and bead portion b at the opposite side of the shoe.

5 When the machine is started, its butting knives, not shown, butt the welt as shown at B, B, Fig. 4, and the anvils 97, 97 are retracted. The bead portions b, b, however, being beneath the anvils, are not butted, but, as the deflectors 60, 60 are moved in by the mechanism described, and in the manner explained in Patent No. 2,206,897, are bent into the positions shown in Figs. 4 and 5, first by surfaces 60b, 60b, and finally by corners between these surfaces and the concave surfaces 15 60c, 60c. The tack nozzles of the machine, not shown, which form part of the welt packing mechanism of the machine, now descend and occupy positions indicated in broken outline at 20 171, 171, and, as they are pressed against the welt and inseam, hold the inturned ends of the bead portions while the crease finder assemblies are moved back to the position shown in Fig. 5 prior to the tacking and pounding operation which now follows. Preferably, the tacker nozzles 171, 171, 25 see Patent No. 2,206,897, are adjusted so that the tacks t, t pass through the inturned ends of the bead portions b, b, as shown in Fig. 5.

As in the machines of the mentioned patents, 30 the crease finder brackets 70 are connected to tacker heads 148, 148 and hence partake of the movements of these heads. These movements are effected by a lever 492 (Fig. 1), operated by means of a cam, not shown, operating through the following mechanism. This lever is keyed to a vertical shaft 494 and has an arm 518 adjacent the outer end of which is swiveled a rod 520. Beneath the lever 492 and freely rotatable on the shaft is a lever 500 having an arm 542. The rod passes through a block 526, swiveled to the end 35 of the arm 542, and a compression spring 522 is interposed between one face of this block and an adjustable abutment 524 on the opposite end of the rod. Angular movements of the arm 518 are thus transmitted to the lever 500 through the spring 522. Beneath the lever 500 is a third arm 532 and this is likewise freely rotatable on the shaft 494. The normal position of this arm is fixed by a link 554 pivoted to the frame and having a slotted end which embraces a pin 562 in the arm. A spring-pressed plunger 560 urges the pin against the end of an adjusting screw 564 by means of which the normal position of the arm 532 may be varied. A pawl 548 is pivoted to the arm 532, and a spring-pressed plunger 572 swings this pawl toward ratchet teeth 546 cut on the arm 542, engagement of the pawl with these teeth being prevented, when the parts are in the positions shown, by a pin 566, carried by arm 518, and an extension 570 of the pawl.

60 The arm 500 is connected to the left-hand head 148 by means of an adjusting screw 506 and a toggle mechanism about to be described, and the heads 148, 148 are connected for conjoint opening and closing movements by means of links 504, 512 and geared levers 580 and 508. The operation of the opening and closing mechanism which has just been described is the same as that shown in Patent No. 2,202,005, see Fig. 23, and pages 8 and 9 of that specification, and is briefly as follows: In Fig. 1, the heads, and also the crease finder assemblies which are connected to the heads, as explained in the patent just mentioned, are being held in open position, as set by 65 suitable adjustment of the screw 506, by means

of springs, not shown. Initial angular movement of the lever 492 in a counterclockwise direction, by means of the operating cam, not shown, is transmitted to arm 500, and also to the brackets and crease finder assemblies, through the spring 522, until the pin 566 moves past the end of extension 570, whereupon the pawl 548 moves into engagement with teeth 546 and a rigid connection between lever 492 and arm 500 is effected. At this time, the arm 532 is being moved in a counterclockwise direction by engagement of an abutment surface 536 of the arm 518. As the operating cam completes a single turn the parts are returned to the positions shown, a spring-pressed plunger 600 striking against a boss 602 on the frame to cushion the stopping of bracket movement. During this return movement the pin 566 releases the pawl 548 from engagement with the teeth 546.

Referring now to the toggle mechanism, which, as a feature of this invention, is interposed between the arm 500, or more specifically the adjusting screw 506, and the arm 502 of the bracket 148, the screw 506 has a fixed collar 202 and passes freely through a block 200 (Fig. 1). Between this collar and a face on the block there is a grooved sleeve 204 also fixed to the shaft and held against this face by means of a compression spring 206 interposed between a collar 203 and the opposite face of the block. A spring-pressed plunger 248 cooperates with the grooved sleeve to hold the screw 506 in any adjusted position to which it may be moved by a hand wheel, not shown. Formed integrally with the block are two oppositely extending studs 210 and 212 (Fig. 2). A hooked arm 214 (Fig. 1) is keyed to stud 212, and above this arm is a bushing 216, likewise keyed to this stud, on which is journaled one end of a link 218. A nut 220 holds these parts on the stud, and a pin 222 connects the other end of this link to the bracket arm 502. Two toggle links 224, 226, connected by a pin 228, extend between the end of the hooked arm 214 and the outer end of the bracket arm 502 to which they are pivoted by means of pins 230, 232. A grasshopper spring 234 holds the toggle straightened, as shown, with an abutment surface 236 on link 226 bearing against an abutment surface 238 on the hooked arm 214. Journaled on the downwardly projecting stud 210 is an angle lever comprising a forwardly extending handle 240 and an arm 242 at right angles thereto. The link 226 has an arm 244 extending at right angles thereto, and a link 246 connects this arm to the arm 242.

With this toggle mechanism it is possible to open the brackets a predetermined amount, indicated by the angle α , Fig. 1, by swinging the handle 240 from the full-line position to the broken-line position shown in Fig. 1, the toggle formed by links 224 and 226 being broken by the swinging of link 226 through link 246, and the parts moving to the broken-line positions shown. As already noted, the crease finder assemblies move with the brackets and hence are opened a corresponding amount, as indicated by the angle α in Fig. 3. With the crease finder assemblies thus separated the operator is enabled easily to insert the one anvil beneath the welt and over the bi-welt strip and then as he brings the crease finder assemblies together again, by moving the handle 240 to the left, insertion of the other anvil beneath the welt and over the bi-welt strip at the other side of the shoe is effected, the crease

finders now being returned to proper position in the welt crease for the particular size shoe being handled. This separating of the crease finder assemblies is effected without disturbing the setting of the crease finders as made by the adjusting screw 506 and the spring 234 assures that the toggle is always returned to its straightened condition when the operator releases the handle 240.

10 Having described my invention, what I claim as new and desire to secure by Letters Patent of the United States is:

1. In a welt butting and tacking machine for operating on a shoe having a two-piece storm 15 welt comprising a welt strip and a separate bead portion, the combination of means for supporting the ends of the welt strip only for the butting operation, and movable means operable after the butting of the welt strips for bending the un- 20 severed ends of the separate bead portion, which extend rearwardly beyond the butted ends of the welt, inwardly toward the middle of the shoe bottom.

2. In a welt butting and tacking machine for 25 operating on a shoe having a two-piece storm welt comprising a welt strip and a separate bead portion, the combination of anvils for supporting the ends of the welt strip only during the welt butting operation so that the unsecured 30 ends of the separate bead portion of the welt are unsevered, and means associated with the anvils and movable during the operation of the machine for bending the unsevered and unsecured ends of the bead portion, which extend rearwardly be- 35 yond the butted ends of the welt, inwardly toward the middle of the shoe bottom.

3. In a welt butting and tacking machine for 40 operating on a shoe having a two-piece storm welt comprising a welt strip and a separate bead portion, the combination of anvils for supporting the ends of the welt strip during the welt butting operation so that the unsecured ends of the bead portion of the welt are unsevered, and deflectors having portions extending beneath the 45 anvils and movable after the welt butting operation for bending the unsevered ends of the bead portion inwardly toward the middle of the shoe bottom.

4. In a welt butting and tacking machine for 50 operating on a shoe having a two-piece storm welt comprising a welt strip and a separate bead portion, the combination of crease finders for engaging the welt crease on opposite sides of a shoe, anvils for supporting the ends of the welt strip during the welt butting operation so that the unsecured ends of the bead portion of the welt are unsevered, and deflectors arranged 55 between said crease finders and said anvils and each having a portion extending inwardly toward the shoe and rearwardly beneath an anvil, said deflectors being movable during the operation of the machine for bending the unsevered ends of the bead portion inwardly toward the 60 middle of the shoe bottom.

5. In a welt butting machine having a pair of 65 crease finder assemblies, each including a crease finder, the combination of adjustable means for variably positioning the assemblies so that the 70 crease finders will accommodate shoes of different sizes, and means for moving the assemblies out of adjusted position to separate the crease finders and for returning the assemblies and their crease finders to their original positions without 75 disturbing the setting of said adjustable means.

6. In a welt butting machine having a pair of crease finder assemblies, each including a crease finder, the combination of adjustable means for variably positioning the assemblies so that the crease finders will accommodate shoes of different sizes, and a toggle mechanism associated with said adjustable means for moving the assemblies out of adjusted position to separate the crease finders and for returning the assemblies and their crease finders to their original positions without disturbing the setting of said adjustable means.

7. In a welt butting machine having a pair of crease finder assemblies each including an anvil, a crease finder and a deflector extending beneath the anvil, the combination of adjustable means for variably positioning said assemblies so that the crease finders will accommodate shoes of different sizes, and manually operable means associated with the adjustable means for moving the assemblies out of adjusted position to separate the crease finders, thus to facilitate the introduction of shoes having two-piece storm welts into the machine with the unsecured ends of the bead portion of the welt beneath the anvils and in engagement with the deflectors, and for returning the assemblies and their crease finders to their original adjusted positions.

8. In a welt butting machine having a pair of crease finder assemblies, each including an anvil, a crease finder and a deflector extending beneath the anvil and movable during the operation of the machine for bending the ends of the bead portion of a two-piece storm welt inwardly of the shoe bottom, the combination of adjustable means for variably positioning said assemblies so that the crease finders will accommodate shoes of different sizes, and a toggle mechanism associated with said adjustable means for moving the assemblies out of adjusted position to separate the crease finders, thus to facilitate the introduction of shoes having two-piece storm welts into the machine with the unsecured ends of the bead portion of the welt beneath the anvils and in engagement with the deflectors and for returning the assemblies and their crease finders to their original adjusted positions.

9. In a welt butting machine having a pair of movable crease finder assemblies, the combination of power-operated means for moving said assemblies during the operation of the machine, adjustable means associated with the power-operated means for initially positioning said assemblies to accommodate different sized shoes,

and a toggle mechanism interposed between the adjustable means and the crease finder assemblies, said toggle mechanism being arranged to effect a separation of the crease finder assemblies when it is broken and to return said assemblies to their original adjusted position when straightened.

10. In a welt butting machine having a pair of movable crease finder assemblies, the combination of power-operated means for moving said assemblies during the operation of the machine, an adjusting screw associated with the power-operated means for initially positioning said assemblies, said adjusting screw being threaded to the power-operated means and having an operative connection with said assemblies including a toggle mechanism, manual means for breaking the toggle to effect a separation of the crease finder assemblies and for straightening the toggle to return the assemblies to their original adjusted position, cooperating stop means on the manual means and the toggle, and a spring normally holding said stop means in engagement and the toggle mechanism straightened.

11. In a welt butting machine having a pair of movable crease finder assemblies and a pair of movable tacker head brackets connected together for conjoint opening and closing movements, the combination of a power-operated member for moving said brackets and said crease finder assemblies, means for connecting said power-operated member to one of the brackets comprising an adjusting screw and a variable length linkage, and manual means for varying the length of the linkage to effect a foreshortening of said connecting means without disturbing the setting of said adjusting screw.

12. In a welt butting machine having a pair of movable crease finder assemblies and a pair of movable tacker head brackets connected together for conjoint opening and closing movements, the combination of a power-operated arm for moving said brackets and said crease finder assemblies, means connecting said arm to one of the brackets comprising an adjusting screw and a toggle mechanism, said screw being threaded into said arm at one end and secured to one link of the toggle at its other end, an operating handle for breaking the toggle mechanism to effect a foreshortening of said connecting means without disturbing the setting of the adjusting screw, and means for normally holding said toggle mechanism straightened.
